UNITED STATES PATENT OFFICE

2,682,758

DEHUMIDIFYING APPARATUS

Arvel R. Harris, Evansville, Ind., assignor to International Harvester Company, a corporation of New Jersey

Application May 13, 1952, Serial No. 287,566

4 Claims. (Cl. 62—140)

1

This invention relates generally to dehumidifying apparatus and more particularly to a refrigeration system adapted to lower the relative humidity of air within an enclosure.

The invention comprises an apparatus having a refrigerant evaporator and a refrigerant condenser arranged in series with means for passing air to be dehumidified first into contact with said evaporator and then into contact with said condenser. As the warm moist air passes into contact with the evaporator, it will be cooled to its dew point and moisture will be condensed therefrom onto the surfaces of the evaporator from which it may be drained by suitable means. The air is then passed over the condenser where it picks up heat from the hot refrigerant gases and is heated to its original temperature. In commercial practice it has been found that apparatus of this type does not operate as efficiently as desired in that the quantity of water removed from the air is sometimes relatively small. It has been determined that the reason for the small amount of condensation is the fact that the evaporator must first lower the temperature of the air from room temperatures to dew point temperatures before moisture will condense therefrom. This means that a large portion of the capacity of the evaporator will be used in removing sensible heat from the air before condensation begins. The present invention is concerned with overcoming this difficulty so that the refrigeration system will remove a larger quantity of moisture.

One object of the present invention is to provide a dehumidifier with a refrigeration system having the evaporator and condenser arranged in series with means for circulating air to be conditioned into contact with said evaporator first, and then into contact with said condenser.

Another object of the invention is to provide means for collecting and removing the water that condenses on the surfaces of said evaporator.

Another object of the invention is to provide a heat exchange element for pre-cooling the air before it contacts said evaporator in order that a substantial portion of the sensible heat of the air will be removed before the air contacts the evaporator.

Another object of the invention is to arrange the heat exchange element between the evaporator and condenser so that incoming air is passed into heat exchange relation with air which has been cooled by said evaporator and is being forwarded to said condenser.

Another object of the invention is to provide means for bypassing room air around said evaporator directly into contact with said condenser.

Another object of the invention is to provide a compact dehumidifying unit which is light in weight and can be easily moved about by one person.

2

Further objects and advantages of the invention will become apparent as the following description proceeds, and the features of novelty which characterize the invention will be pointed out with particularity in the claims annexed to and forming a part of this specification.

For a better understanding of the invention, reference may be had to the accompanying drawings in which:

10 Fig. 1 is a vertical sectional view of a dehumidifying unit embodying the features of the invention.

Fig. 2 is a cross-sectional view of the unit taken along line 2—2 of Fig. 1.

15 Fig. 3 is a vertical sectional view of a modified form of the invention.

Fig. 4 is a cross-sectional view of the unit taken along line 4—4 of Fig. 3.

20 Fig. 5 is a cross-sectional view of the unit taken along line 5—5 of Fig. 3.

25 Referring to Figs. 1 and 2 of the drawings for a detailed description of the invention, a dehumidifying unit is designated generally by reference numeral 10. The unit 10 comprises an outer metallic casing 11 having a top wall 12, side walls 13 and 14, and end walls 15 and 16. Positioned within the casing 11 is a refrigeration system comprising a hermetically sealed motor-compressor unit 17, an evaporator 18, and condenser 19. The refrigeration system is charged with a suitable refrigerant which is compressed by the motor-compressor unit 17 during operation thereof and then conveyed by conduit 20 to condenser 19. As the refrigerant flows through condenser 19, it is cooled and condensed and then flows therefrom through a capillary restrictor tube 21 to evaporator 18. After being heated to a vapor during its passage through the evaporator 18, the refrigerant is returned to the motor-compressor unit 17 through conduit 22 to be recompressed and forwarded through the system again.

30 In the modification shown in Figs. 1 and 2, the motor-compressor unit 17 is secured to end wall 15 by mounts 23. Condenser 19 is secured to top wall 12 by bolts 24. Secured to top wall 12 by brackets 25 and bolts 26 is an electric motor 27 having an armature shaft 28 on which a propeller type fan 29 is mounted adjacent to condenser 19. End wall 15 is provided with an opening 30 therethrough adjacent to motor 27 with vanes 31 secured therein for the purpose of directing air currents therethrough. A partition 34 is positioned below the condenser 19 and the motor 27. A shroud 32 is secured to condenser 19 and is arranged to enclose fan 29 so that when motor 27 is running, the fan 29 will 35 pull air through the condenser 19 and force it through the opening 30. The evaporator 18 is

spaced from the condenser 19 and attached to top wall 12 by brackets 33 and bolts 34. Positioned below evaporator 18 is a receptacle 35 which may be a common household bucket. End wall 16 is provided with a rectangular shaped opening 36 through which the receptacle 35 may be inserted and removed.

Positioned between condenser 19 and evaporator 18 is a heat exchange unit 37 comprising an outer horizontal duct 38 having side walls 39 and 40 and inclined top wall 41 and bottom wall 42. One end of the duct 38 is secured to the edges of the condenser 19 in sealed relationship whereas the other end is secured to the evaporator 18 in sealed relationship so that air being circulated by fan 29 will pass first through said evaporator and then through said condenser. Bottom wall 42 of duct 38 is provided with a small opening 43 adjacent condenser 19 with vanes 44 secured therein for the purpose of directing streams of air passing therethrough.

Bottom wall 42 and top wall 38 are provided with spaced apart slots in which the ends of upright ducts 45 are secured. The upright ducts 45 are spaced between side walls 39 and 40 and are secured thereto by straps 46. As seen in Fig. 2, the straps have semi-circular shaped grooves therein which receive the curved walls of the ducts 45. The straps 46 may be arranged to clamp the ducts 45 therebetween or suitable means, such as spot welding, may be employed to permanently attach the ducts to the straps.

A curved duct 47 having top wall 48, end wall 49, bottom wall 50, and side walls 51 and 52 is positioned with bottom wall 50 secured to evaporator 18 and an offset edge 53 of top wall 48 secured to top wall 41 of horizontal duct 37. The side walls 51 and 52 of the curved duct 47 engage the horizontal duct 48 and the sides of evaporator 18 and seal thereagainst so that air being drawn through evaporator 18 by fan 29 will be pulled from upright ducts 45 through curved duct 47.

The operation of the motor-compressor unit 17 and electric motor 27 may be controlled automatically or manually. When dehumidification of air is needed, both the motor 27 and motor-compressor unit 17 are energized from a suitable electric supply. With the motor-compressor unit 17 operating, the refrigerant will be circulated through the refrigeration system as explained heretofore whereby the surfaces of the condenser 19 will be maintained at a high temperature and the surfaces of the evaporator 18 will be maintained at a low temperature. Air to be dehumidified is pulled in opening 36 by fan 29, circulated upwardly through upright ducts 45, through curved duct 47, over evaporator 18, through horizontal duct 38, over condenser 19 and then expelled from the casing 11 through opening 30. As the air passes over the cold surfaces of the evaporator 18, it will be cooled below its dew point and the water vapor carried thereby will be condensed onto the surfaces of the evaporator, from which it will drain into receptacle 35. The air then passes through duct 38 over the hot surfaces of the condenser 19 where it will be re-heated to substantially the same temperature as when it entered the casing 11.

As mentioned heretofore, the purpose of the heat exchange unit 37 is to pre-cool the air before it contacts the evaporator 18 so that most of the sensible heat is removed thereby. The chilled air which is flowing between the evaporator 18 and the condenser 19 wipes over the

outer surfaces of the upright ducts 45. Since the air being pulled upwardly through the upright ducts 45 is at a higher temperature, there will be a transfer of heat between the hot air flowing through the upright ducts 45 and the cold air flowing through horizontal duct 38. This transfer of heat cools the air within upright ducts 45 to a temperature approaching the dew point of the air so that the greater portion of the capacity of the evaporator 18 is used in condensing water from the air, or, in other words, removing latent heat from the air. The opening 43 in the bottom wall 42 of duct 38 allows a limited volume of air from opening 36 to flow directly over the condenser 19, and vanes 44 may be made adjustable in order that the volume of air may be controlled. The air flowing through opening 43 aids in cooling the condenser, and since this will reduce the volume of air flowing through evaporator 18, a greater amount of heat will be removed from this air by the evaporator.

Figs. 3, 4 and 5 illustrate a modification of the invention in which the parts thereof are arranged in a different manner. The outer casing 54 of the unit is positioned upon a floor 55 and is provided with a top wall 56, end walls 57 and 58, and side walls 59 and 60. The interior of the casing 54 is divided into an upper compartment 61 and a lower compartment 62 by partition 63. The condenser 64 is located in the upper compartment 61 and is secured to partitions 63 by bolts 65. The evaporator 66 is located in lower compartment 62 and is fastened to partition 63 by bolts 67. The motor-compressor unit 68 is secured to partition 63 by resilient mounts 69 with the outlet thereof connected to condenser 64 by conduit 70 and the inlet thereof connected to the evaporator 66 by conduit 71. A capillary tube 72 connects the condenser 64 and evaporator 66 and the refrigeration system operates in the same manner explained above with reference to Figs. 1 and 2. The compressed refrigerant flows from compressor 63 through conduit 70, condenser 64, capillary tube 72, evaporator 66, conduit 71 and back to compressor 63 to complete the cycle.

End wall 58 is provided with an intermediate opening 73 and a top opening 74 in which are secured vanes 75 and 76 respectively. Evaporator 66 is connected to intermediate opening 73 by a heat exchange element 77 comprising a horizontal duct 78 having a bottom wall 79 and side walls 80 and 81. Duct 78 is secured to partition 63 by brackets 82 with the side walls 80 and 81 contacting said partition. Bottom wall 79 and partition 63 are provided with openings 83 therethrough into which the ends of upright ducts 83 are inserted. The upright ducts 83 are held in place by straps 84 having the ends thereof secured to side walls 80 and 81. An electric motor 85 is positioned in upper compartment 61 and is secured to partition 63 by brackets 86 and bolts 87. A fan 88 is mounted upon the armature shaft 89 of motor 85 adjacent condenser 64 and a shroud 90 surrounds the fan 88 and is secured to condenser 64. End wall 57 is provided with an outlet opening 91 adjacent motor 85 with vanes 92 secured therein. A receptacle 93 is positioned upon floor 55 below evaporator 66 so that it will collect any water which drains from the surfaces of the evaporator 66.

When air is to be dehumidified by the unit, the motor 85 and motor-compressor unit 68 are energized simultaneously so that the refrigeration system will operate and air will be circulated

by fan 88. The air is pulled into the casing 54 through opening 73 and circulated through horizontal duct 78 around upright ducts 83 and through evaporator 66. The air then flows downwardly around receptacle 93 and up through upright ducts 83, around the motor-compressor unit 68, through condenser 64, and out opening 91. Water from the air will condense on the cold surfaces of the evaporator 66 and drain into receptacle 93 which may be removed for emptying by raising the unit 54 from the floor 55. The air will be reheated to its incoming temperature by the hot surfaces of the condenser 64. The heat exchange unit 77 will pre-cool the air before it strikes the surfaces of the evaporator 66 by the transfer of heat to the cold air flowing upwardly through upright ducts 83 from evaporator 66 to condenser 64 as explained more thoroughly in the description of Figs. 1 and 2. Room air will flow directly into contact with condenser 64 through top opening 74 so that the temperature of the evaporator will be held at a lower value whereby a larger quantity of water will be condensed from the air.

As is readily apparent from the preceding description, the present invention provides a dehumidifier which will operate to remove a large quantity of water from air having a high relative humidity. The heat exchange unit placed between the condenser and evaporator provides a means of pre-cooling the incoming air before it contacts the evaporator and allows a greater portion of the capacity of the evaporator to be used for removing latent heat from the air. By providing the bypass opening for passing air directly into contact with the condenser, a smaller volume of air will flow over the surfaces of the evaporator whereby the temperature of the evaporator will be maintained at a lower value. The components of the dehumidifier are arranged in a compact manner and the unit is light in weight so that it can be easily lifted and carried by one person. The receptacle for collecting condensate is of such size that it will hold a large quantity of water and is arranged in a manner which permits quick removal for emptying.

It will, of course, be understood that various changes in details of construction and arrangement of parts may be made by those skilled in the art without departing from the spirit of the invention as set forth in the appended claims.

What is claimed is:

1. In apparatus for dehumidifying the air within an enclosure, a casing, a horizontally disposed wall mounted within said casing dividing said casing into upper and lower compartments, a refrigerant condenser and a refrigerant evaporator having inlet and outlet sides for the passage of air therethrough, said refrigerant evaporator mounted to said wall within said lower compartment, said casing having an inlet opening formed through one vertical wall thereof and positioned adjacent said lower compartment, said casing having an outlet opening formed through another vertical wall thereof adjacent said upper compartment, an air-to-air heat exchanger having first and second ducts therethrough in thermal contact, said air-to-air heat exchanger mounted to said wall within said lower compartment, said first duct of said air-to-air heat exchanger connected to said inlet opening and said inlet side of said evaporator, said second duct connected between said upper and lower compartments through an opening provided in said wall, said refrigerant condenser mounted to said wall

within and substantially across said upper compartment between said outlet opening and said second duct of said air-to-air heat exchanger, a motor-compressor unit for the operation of said refrigerant evaporator and said refrigerant condenser mounted to said wall within said upper compartment substantially over a portion of said second duct, fan means mounted to said wall within said upper compartment between said outlet opening and said outlet side of said refrigerant condenser, said fan means operable to draw air from said enclosure into and through said inlet opening, into and through said first duct of said air-to-air heat exchanger, into said inlet side of said refrigerant evaporator, through said refrigerant evaporator, from the outlet side of said refrigerant evaporator through said lower compartment, into and through said second duct of said air-to-air heat exchanger, into said upper compartment and over the surfaces of said motor-compressor unit, into said inlet side of said condenser, through said refrigerant condenser, from the outlet side of said refrigerant condenser through the remainder of said upper compartment and through and out of said outlet opening, whereby said air is precooled by the transfer of heat to said first duct, whereby the air is cooled to the dew point temperature thereof and water is condensed upon the surfaces of said evaporator, whereby the air is then heated as it passes through said second duct of said air-to-air heat exchanger, whereby said motor-compressor unit then transfers heat to said air and whereby said air is further heated by passage through said refrigerant condenser and projected into said enclosure, when said motor compressor unit is operating.

2. In apparatus for dehumidifying the air within an enclosure as claimed in claim 1, a bypass opening formed through said one vertical wall of said casing and positioned adjacent said upper compartment, whereby air from said enclosure is drawn through said bypass opening over the surfaces of said motor-compressor unit, through said refrigerant condenser, and out of said outlet opening when said fan means are operating.

3. In an apparatus for dehumidifying the air within an enclosure as claimed in claim 1, a condensate receptacle removably mounted within said lower compartment below said refrigerant evaporator, whereby any water condensed upon the surfaces of said refrigerant evaporator is collected within said condensate receptacle.

4. In apparatus for dehumidifying the air within an enclosure as claimed in claim 3, said casing being provided with a receptacle opening on the underside thereof, said receptacle opening having a size sufficient to admit said condensate receptacle therethrough, whereby said condensate receptacle is removable and replaceable into said lower compartment through said receptacle opening.
